Primary Examiner — Katie Jane Stofko

(74) Attorney, Agent, or Firm — Zagorin Cave LLP;
Robert W. Holland(57) **CLAIM**

We claim the ornamental design for a foldable monitor hood, as shown and described.

DESCRIPTION

FIG. 1 is a front perspective view of a foldable monitor hood comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

Broken lines shown in the drawings illustrate portions of the foldable monitor hood, and form no part of the claimed design.
